CIGARETTE HOLDER

Filed April 29, 1933

UNITED STATES PATENT OFFICE

2,002,494

CIGARETTE HOLDER

William Eisenberg, Minneapolis, Minn.

Application April 29, 1933, Serial No. 668,489

4 Claims. (Cl. 206—41)

My invention relates to cigarette holders and has for its object to provide a holder by means of which lighted cigarettes may be safely supported upon the person of the smoker.

An object of the invention resides in providing a cigarette holder adapted to completely encase the cigarette.

A still further object of the invention resides in providing a cigarette holder in which the cigarette is maintained lit while supported thereby.

An object of the invention resides in constructing the cigarette holder with an ejector by means of which the cigarette may be readily removed from the holder when desired for use.

Another object of the invention resides in providing a cigarette holder which may be easily attached to the wearing apparel of the smoker and supported in an accessible and convenient manner.

Other objects of the invention reside in the novel combination and arrangement of parts and in the details of construction hereinafter illustrated and/or described.

In the drawing:

Fig. 1 is a perspective view of the cigarette holder illustrating an embodiment of my invention and showing the same attached to the belt of the smoker.

Fig. 2 is a longitudinal sectional view taken on line 2—2 of Fig. 1.

Fig. 3 is a view similar to Fig. 2 showing the ejector and cigarette in raised position.

Fig. 4 is a plan sectional view taken on line 4—4 of Fig. 2 with the cigarette removed from the holder.

Fig. 5 is a perspective view of the ejector.

Fig. 6 is a developed view of the blank from which the sheath of the cigarette holder is constructed.

Fig. 7 is a developed view of the blank from which the ejector of the cigarette holder is constructed.

Fig. 8 is a plan view of another form of the invention.

Fig. 9 is an elevational sectional view taken on line 9—9 of Fig. 8.

In participating in outdoor sports and particularly in golf, considerable inconvenience is encountered by smokers in the disposition of lighted cigarettes or cigars during the playing of the ball and in other instances. The present invention forms a practical and convenient holder whereby a cigarette, cigar or similar smoker's article may be conveniently supported and maintained lit while the smoker is engaged in other

activities and again procured for use whenever desired.

The form of my invention shown in Fig. 1 comprises a tubular sheath indicated in its entirety at 10, which sheath is formed with a bottom 11 and is provided with a flared mouth or opening 12 at its upper end. From the wall structure of the sheath 10 issues a hook 13 adapted to hook about the belt of the wearer which has been partly illustrated at 14, in Fig. 1. The sheath 10 is constructed with a chamber 15 upon the interior thereof which communicates with the exterior through the opening or mouth 12. This chamber is of such dimensions as to freely receive a cigarette or cigar, as the case may be when the same is inserted endwise into the said chamber through the mouth 12 of the device.

The sheath 10 is preferably constructed of sheet metal and in such case is formed from a blank 20 indicated at 16 in Fig. 6. This blank is provided with a rectangular body portion 17 having a number of V-shaped ears 18 at the lowermost end thereof. The upper part of the blank 16 flares outwardly as designated at 19 and is provided with a narrow extension 20 which when properly folded forms the hook 13. The lateral edges 21 and 22 of this blank are recessed as indicated at 23 and 24. In the construction of the sheath 10 the body portion 16 is bent about a suitable cylindrical mandrel, the upper end of which is flared and the lateral edges 21 and 22 of the blank brought together. This causes the two recesses 23 and 24 to meet and form a slot 25 extending partially along the sheath, the ends of said slot being indicated at 26 and 27. The bottom 11 is constructed by bending the ears 18 inwardly which are so designed and proportioned as to meet one another and to form a tight closure for the lower end of the sheath.

Within the interior of the sheath 10 is slidably mounted an ejector 28 which is shown in detail in Figs. 4 and 5. This ejector is constructed from a blank 29 illustrated in Fig. 7 which is of a width equal to the circumferential dimension of the ejector and which is formed with lateral edges 30 and 31. This blank is constructed at the lowermost portion thereof with ears 32 which are similar in shape to the ears 18, excepting that the same are truncated and of smaller dimensions, said ears being spaced apart as shown in Fig. 4. The ejector 28 is constructed in a manner similar to the sheath 10 by forming the same about a suitable mandrel causing the lateral edges 30 and 31 of the blank 29 to meet each other. The ears

32 are also bent inwardly toward one another and when properly formed, become spaced from one another to provide spaces 33 extending across the lowermost portion of the ejector and through which ashes on the cigarette may readily sift.

From the body structure of the blank 29 is formed a finger piece 35. This finger piece is struck out of the blank and is bent outwardly from the body of the ejector as shown in Fig. 5. 10 Finger piece 35 is constructed with a head 36 and a neck 37 issuing from the body of the ejector. This finger piece is of such dimensions that the neck 37 thereof slides freely along the slot 25, while the head 36 thereof extends outwardly beyond the exterior of the sheath 10 where the same may be readily engaged by the finger of the user. The body of the ejector 28 is of such dimensions as to slide freely within the interior of the tubular sheath 10 and to receive the cigarette and may be moved through the finger piece 35 from one 20 end of the slot 25 to the other.

In the use of the device the holder is hooked upon the belt of the wearer by placing the hook 13 over the upper edge of the same and drawing 25 the holder downwardly. This causes the holder to become firmly attached to the belt and supported in a manner to expose the flared mouth 12 of the sheath. In normal position, the ejector 28 is at its lowermost position. With the parts 30 so arranged a cigarette such as indicated at 33 may be inserted endwise into the chamber 15 within the sheath 10 through the flared mouth 12 thereof. The lighted end 39 of the cigarette 38 is placed downwardly and rests upon the ears 32 35 which form a previous bottom for the said ejector through which the ashes from the lighted end 39 of cigarette 38 may sift. In order to maintain the cigarette lighted, a number of holes 40 are drilled in the body 11 of the sheath 10 immediately above the bottom 11 thereof and forwardly of the holder. Similar holes 41 are drilled in the body of the ejector 28 and are adapted to register with the holes 40 when the ejector is in its lowermost position as shown in Fig. 2. By means of 40 these holes, air is admitted to the lighted end of the cigarette and combustion thereby maintained.

It will be noted that the slot 25 is of such length that the bottom 42 of the ejector 28 extends above the bottom 11 of the sheath. It will 50 also be noted that the lowermost of the holes 40 are somewhat above said bottom 11 so that a receptacle 43 is formed at the lower end of the sheath, in which the ashes falling from the cigarette through the openings 33 in the bottom 42 55 of ejector 28 may be collected. This receptacle serves to prevent sparks from the cigarette being promiscuously discharged and prevents the unintentional starting of fires. At the same time the ashes from the cigarette are maintained in 60 this receptacle and prevented from being discharged upon the clothing of the smoker.

After a cigarette has been placed within the sheath 10 as shown in Fig. 2, the same is completely encased and sheathed so that the cigarette is protected from injury and at the same time the lighted end thereof is prevented from coming in contact with the person of the user or with his apparel. Whenever the cigarette is again desired for use, it is merely necessary to 65 raise the ejector 28 by lifting the finger piece 35 upwardly to its position shown in Fig. 3 in which the said finger piece is near the end 26 of slot 25. The upper end of the cigarette is then brought above the open mouth 12 of the sheath, giving 70 75 access to the same.

In Figs. 8 and 9 I have shown a slight modification of the invention in which the sheath is supported through a tray 44 instead of through the hook 13. The parts of the sheath and ejector in this form of the invention being substantially identical with those of the other form, will not be again described and such parts will be indicated by the same reference characters.

The tray 44 may be constructed from metal and is formed with a bottom 46 having an outwardly flaring portion 47 extending upwardly therefrom. This portion terminates in a rim 48 which finishes the upper edge of the tray. A handle 49 may be secured to the tray whereby the device may be carried about as desired. In the tray 44 is provided a false bottom 50 forming a chamber or receptacle 51 within the tray in which ashes may be accumulated and confined. The false bottom 50 is received within a groove 53 formed in the 20 portion 47 of tray 44 and is held in position in said groove through a bead 54. A thimble 51 is formed in the center of the false bottom 50, which thimble is constructed with an opening 52 communicating with the interior of the receptacle 51.

The sheath 10 of this form of the invention is constructed without a bottom at its lower end and is provided with a nipple 45 which is adapted to be received within the thimble 51. Both the thimble 51 and nipple 45 are conical or tapered in form so that the sheath may be applied to and held attached to the tray 44 through frictional engagement of the nipple with the thimble. To maintain the cigarette lighted, the nipple 45 is 35 constructed with openings 55 which register with openings 56 in the thimble 51. All of these openings register with the openings 33 in the ejector 28 so that air may reach the lighted end 39 of the cigarette. In addition to these openings 40 other openings 57 are provided in the false bottom 50 through which air may enter the chamber 51 and reach the lighted end of the cigarette through the opening 33 in the ejector 28.

The use of the invention shown in Figs. 8 and 9 45 is similar to that shown in Fig. 1. The cigarette is placed into the sheath 10 and the ejector 28 manipulated as previously described when it is desired to remove the cigarette therefrom. The various openings described cause air to reach the lighted end of the cigarette and maintain combustion. All of the ashes falling from the cigarette are collected in the receptacle 51. When the same becomes full, the sheath 10 may be removed and the tray inverted to cause the ashes to 55 be discharged from said receptacle through the opening 52 therein.

In the description of my invention, I have referred to the same as a cigarette holder. It can, however, be readily comprehended that the device 60 may be used equally as well for cigars or other forms of smoker's articles, and the word "cigarette" as used in the specification and claims is intended to embrace all such forms of smoker's 65 articles.

My invention is highly advantageous in that an extremely practical and simple construction is provided by means of which the desired results are readily accomplished, without danger 70 of burning the person or the wearing apparel of the user. With my invention the smoker may consume the entire cigarette without interrupting the progress of the game or without disturbing his other activities. The device can be con- 75

structed at a nominal cost and is not apt to get out of order.

Changes in the specific form of my invention, as herein disclosed, may be made within the 5 scope of what is claimed without departing from the spirit of my invention.

Having described my invention, what I claim as new and desire to protect by Letters Patent is:

1. A cigarette holder for sheathing a lighted cigarette and maintaining the same lighted pending its subsequent use, said holder comprising a tubular sheath, means for supporting the same in upright position, said sheath being adapted to receive a cigarette, lighted end foremost, an 10 ejector movable up and down within the sheath and adapted normally to occupy a position at the lower portion of the sheath, said sheath having a slot therein, a finger piece issuing from the 15 ejector and extending through said slot for elevating the ejector in the sheath to project a contained cigarette therefrom, said ejector providing a perforate rest for the lighted end of the cigarette, said sheath providing an ash receiving chamber beneath said ejector, the side wall of 20 said sheath having a perforation therein beneath the elevation normally occupied by said ejector, said perforation and said slot providing for a natural supply of combustion supporting air to the 25 burning end of the cigarette resting on said ejector.

2. A cigarette holder for sheathing a lighted cigarette and maintaining the same lighted pending its subsequent use, said holder comprising a tubular sheath, means for supporting the same in upright position, said sheath being adapted to receive a cigarette, lighted end foremost, an 30 ejector movable up and down within the sheath and adapted normally to occupy a position at the lower portion of said sheath, means for elevating the ejector in the sheath to project a contained cigarette therefrom, said ejector providing a perforate rest for the lighted end of the cigarette, said sheath providing an ash receiving chamber beneath said ejector, the side wall of 35 said sheath being perforate above and beneath the elevation normally occupied by the ejector to provide for a natural supply of combustion supporting air to the burning end of the cigarette resting on said ejector.

3. A cigarette holder for sheathing a lighted cigarette and maintaining the same lighted pending its subsequent use, said holder comprising an elongated sheath, means for supporting the same in upright position, said sheath being adapted to receive a cigarette, lighted end foremost, an ejector movable up and down within the sheath and adapted normally to occupy a position at the lower portion of said sheath, means for elevating the ejector in the sheath to project 10 a contained cigarette herefrom, said ejector providing a perforate rest for the lighted end of the cigarette, said sheath providing an ash receiving chamber beneath said ejector, the side wall of 15 said sheath being perforate adjacent the elevation normally occupied by the ejector to admit air directly to the burning end of the cigarette resting on said ejector.

4. A cigarette holder for sheathing a lighted cigarette and maintaining the same lighted pending its subsequent use, said holder comprising a tubular sheath, means for supporting the same in upright position, said sheath being adapted to receive a cigarette, lighted end foremost, a cup-like ejector movable up and down within the 20 sheath, said sheath having a slot therein extending longitudinally thereof, a finger piece issuing from the ejector and extending through said slot, the ends of said slot forming limit stops for the 25 ejector, the lower stop serving normally to position the ejector at the lower portion of said sheath, said ejector being adapted to be elevated in the sheath to project a contained cigarette therefrom, the wall of said ejector having a perforation 30 therein, said ejector having a perforate bottom 35 forming a rest for the lighted end of the cigarette, said sheath having an imperforate bottom and providing an ash receiving chamber between its said imperforate bottom and the perforate bottom of said ejector, the side wall of said sheath 40 having a perforation with which the perforation in the wall of the ejector registers in the normal position of said ejector, said perforations and said slot providing a natural supply of combustion supporting air to the burning end of the cigarette 45 resting on said ejector.
